T. E. AHO,
STAND FOR SHOEMAKERS.
APPLICATION FILED SEPT. 1, 1917.

1,270,682.

Patented June 25, 1918.

UNITED STATES PATENT OFFICE.

TAHVAN E. AHO, OF CROSBY, MINNESOTA.

STAND FOR SHOEMAKERS.

1,270,682.

Specification of Letters Patent. Patented June 25, 1918.

Application filed September 1, 1917. Serial No. 189,309.

To all whom it may concern:

Be it known that I, TAHVAN E. AHO, citizen of the United States, residing at Crosby, in the county of Crow Wing and State of Minnesota, have invented certain new and useful Improvements in Stands for Shoemakers, of which the following is a specification, reference being had to the accompanying drawings.

10 This invention relates to certain improvements in stands for shoemakers, and it is an object of the invention to provide a device of this general character having novel and improved means whereby the device may be 15 readily and conveniently adjusted in order to permit a last applied to the stand to assume the different positions necessary during a repairing operation.

The invention consists in the details of 20 construction and in the combination and arrangement of the several parts of my improved stand whereby certain important advantages are attained and the device is rendered simpler, less expensive and otherwise 25 more convenient and advantageous for use, all as will be hereinafter more fully set forth.

The novel features of the invention will hereinafter be definitely claimed.

30 In order that my invention may be the better understood, I will now proceed to describe the same with reference to the accompanying drawings; wherein—

Figure 1 is a view partly in elevation 35 and partly in section illustrating a stand constructed in accordance with an embodiment of my invention;

Fig. 2 is an elevational view of the lower portion of my improved stand as herein embodied;

Fig. 3 is a sectional view taken substantially on the line 3—3 of Fig. 1;

Fig. 4 is a fragmentary elevational view 45 illustrating a means for locking the rotatable sleeve as herein included against rotation; and

Fig. 5 is a fragmentary detailed sectional view illustrating the locking bolt as included in the structure particularly illustrated in 50 Fig. 4.

As disclosed in the accompanying drawings; B denotes a base adapted to be suitably anchored to any desired support, and which is provided at one side portion with an 55 upstanding bracket 1, having its inner face

preferably flat and unobstructed. The upper portion of the bracket 1, at opposite sides thereof, is provided with the inwardly and upwardly directed, transversely separated perforate ears 2, through which is 60 adapted to be directed the pintle or pin 3. The pintle or pin 3 is also adapted to be loosely disposed through the upper portion of a block or body 4, having one face flat and unobstructed and adapted to contact 65 with the flat face of the bracket 1 when said block or member 4 is vertically disposed. The lower end of the block or member 4 is also adapted to rest upon the base B when said member or bracket is in its vertical 70 position.

The member or block 4 is provided with a longitudinally disposed bore 5, in which is mounted for rotary movement a sleeve 6, and the upper end portion of the sleeve 75 6 is provided with an outstanding annular flange 7, adapted to rest upon the upper edge of the block or member 4. The periphery of the sleeve 6 is provided with longitudinally spaced annular grooves 8, and extending within the upper groove 8 is the pintle or pin 3 hereinbefore referred to; while extending within the lower or second groove 8 is a pin 9, also directed through the block or member 4. By this arrangement it will 85 be at once self-evident that the sleeve 6 will be held against independent movement longitudinally of the bore 5 of the block or member 4 although it is free to rotate.

The under face of the flange 7 is provided 90 with an annular series of recesses or pockets 10, with which coacts the bolt 11 for holding the sleeve 6 against rotation. The bolt 11 is mounted for endwise movement in the longitudinally disposed recess 12 formed in 95 the upper edge of the block or member 4, and which is constantly forced outwardly or upwardly through the medium of the expansible member 14, interposed between the inner end of the bolt 11 and the base of the 100 recess 12. The movement of the bolt 11 under the influence of the expansible member 14 is limited by the outstanding member 15, carried by the bolt 11 and extending exteriorly of the block or member 4 through the cam slot 16, produced in the outer face of the block or member 4 and in communication with the recess 12. The member 15 also coacts with the slot 16 to hold the bolt 11 in a retracted position so that the sleeve 110

6 may be freely and readily rotated when the requirements of practice may so necessitate.

The block or member 4 is also adapted to be swung about the pintle or pin 3 in order that the longitudinal axis of said block or member 4 may be inclined as occasioned by the necessities of practice. In order to maintain the block or member 4 in its various adjustments about the pintle or pin 3, I have freely engaged with the pintle or pin 9 an end portion of the arcuate arm 16, said end portion of the arm 16 extending through an elongated vertically disposed opening 17, formed in the flat face of the block or member 4, and in communication with the bore 5 of the said block or member 4 adjacent the lower annular groove 8. The outer or free end portion of the arcuate arm 16 is loosely directed through an opening 18, produced in the upper end portion of the bracket 1, and the upper face or edge of said arm 16 is provided with a plurality of longitudinally spaced notches 19, in which is adapted to seat a locking arm 20, overlying the outer face of the bracket 1. As herein disclosed, the upper portion of the bracket 1 is provided adjacent its opposite sides with the upwardly directed lugs 21, and an end portion of said locking arm 20 is pivotally supported between one of said lugs and the outer face of the bracket 1, as indicated at 22, while the opposite or free end of the locking arm 20 is adapted to seat between the second lug 21 and the outer face of the bracket 1, when said locking arm 20 is in operative engagement with the arcuate arm 16.

The sleeve 6 has its bore 23 angular in cross section and tapering toward its lower end. S denotes the standard or shank comprised in my improved stand, and which has its lower end portion reduced, as indicated at 24, and adapted to snugly fit within the bore of the sleeve 6. The outer or upper end of the standard or shank S is adapted to have operatively engaged therewith a last L.

From the foregoing description, it is thought to be obvious that a stand constructed in accordance with my invention is of an extremely simple and comparatively inexpensive nature and is particularly well adapted for use by reason of the convenience and facility with which it may be assembled, and it will also be obvious that my invention is susceptible of some change and

modification without material departure from the principles and spirit thereof and for this reason I do not wish to be understood as limiting myself to the precise arrangement and formation of the several parts herein shown in carrying out my invention in practice, except as hereinafter claimed.

I claim:

1. A shoemaker's stand comprising a base provided with an upstanding bracket the inner face of said bracket being substantially flat and unobstructed, inwardly and upwardly directed ears carried by the upper portion of the bracket at opposite sides thereof, a tubular block adapted to rest upon the base when in substantially a vertical position, a face of said tubular block being substantially flat and unobstructed and adapted to contact with the inner face of the bracket, a sleeve extending within the block and rotatably supported by said block, the periphery of the sleeve being provided with an annular groove, a pin disposed through the ears of the bracket and through the block for pivotally supporting the block, said pin also extending within the annular groove of the sleeve and serving to hold said sleeve against endwise movement, and a last standard engaged with the sleeve.

2. A shoemaker's stand comprising a base provided with an upstanding bracket, a tubular block swingingly supported by said bracket, a sleeve insertable within the tubular block and rotatably supported thereby, the periphery of said sleeve having an annular groove, a wall of the block and the bracket being provided with openings adapted to register one with the other and with the annular groove in the sleeve when said block is in contact with the bracket, a pin disposed through the sleeve and extending within the annular groove, an arcuate arm extending through the openings in the bracket and the block and pivotally engaged with the pin at a point within the annular groove, and means carried by the outer face of the bracket and engaging the arcuate arm for holding the block against swinging movement.

In testimony whereof I hereunto affix my signature in the presence of two witnesses.

TAHVAN E. AHO.

Witnesses:

A. J. HAYES,
H. H. GAEWIN.
